Patented Nov. 24, 1914.

UNITED STATES PATENT OFFICE

LOUIS BOWERMAN, OF PORTLAND, OREGON.

CONCENTRATOR.

1,118,393.

Specification of Letters Patent. Patented Nov. 24, 1914.

Application filed November 12, 1913. Serial No. 800,508.

To all whom it may concern:

Be it known that I, LOUIS BOWERMAN, a citizen of the United States, residing at Portland, in the county of Multnomah and State 5 of Oregon, have invented certain new and useful Improvements in Concentrators, of which the following is a specification.

The object of my invention is to produce certain improvements in concentrators, 10 whereby the separation of dry ores is facilitated.

My invention relates to apparatus for separating substances of different specific gravities in substantially pulverulent form 15 as to portions thereof at least, and consists of means for effecting such separation more expeditiously and thoroughly than by those in ordinary use.

In the accompanying drawing: Figure 1 20 is a perspective view partially broken away, of a concentrator box embodying my invention. Fig. 2 is a partial longitudinal vertical section of the subject matter of Fig. 1, on an enlarged scale and which in connection 25 with Fig. 3 illustrates the details of my invention. Fig. 3 is a section of my device taken as upon the line A—A of Fig. 2.

Referring to the numerals on the drawing, 1 indicates the inclined floor of a concentrator top frame 5, which is set upon top of a box 8 to which it is removably fixed in use as by depending strips 6. The box 8 is divided by transverse partitions 19 spaced to accommodate drawers 7, which respectively slide between a partition and a guide plate 13. The top 5 is adapted to be vibrated upon the upper edges of the partitions 19, to impart motion to the material carried upon it.

40 The floor 1, besides being provided with a series of projections 2 preferably in staggered arrangement or other suitable means for spreading the material to be separated evenly upon the floor, has a series of riffles 45 composed of properly spaced bars. Each series lies flush with the floor, but may be disposed at different angles to its longitudinal axis. Those indicated by the numeral 3 are at right angles and those indicated by 4 50 are at oblique angles to said axis. Otherwise the bars of the different series may be identical in shape and as indicated by 3 in Fig. 2.

Each series of riffles is superposed above a 55 drawer 7 into which delivery from its riffles

is made through a chute defined as by side pieces 11 and 12 secured to the bottom of the floor 1 and transversely thereto. The side piece 12 is preferably sustained by the contiguous back piece 11. The pieces 11 make 60 close joints against the upper edges of partitions 19, thereby constituting of each drawer compartment a chamber of substantially airtight fitments with exception of the open bar tops.

In the rear of the several drawers 7 is an air chamber 20 defined in the lower corner of the box 8 by inclined partition wall 21, having a door 18 for each drawer. Each door is hinged as indicated at 15 and is also provided with a wing screw 16 that impinges against the door below its hinge in such manner as to admit of opening and closing the door from the outside of the box 8 through manipulation of the screw.

With the chamber 20 communicates an air supply pipe 17 which is provided for delivery of air under pressure, from a source not illustrated, to the chamber.

For the accommodation of the respective 80 riffles open spaces in the floor 1 are provided of an extent to conform to that of the riffles and bounded on opposite sides with lips 9 and 10 which lie parallel and in close juxtaposition to the bars of the riffle, as indicated 85 by 3 in Fig. 2.

The bars 3 are spaced equally with respect to one another and to the lips 9 and 10, and are of the shape in cross-section illustrated in Fig. 2, wherein, as appears, the upper forward angle α of each defines with the next adjacent member a constricted air discharge slit. Each angle α is depressed below the plane of the floor 1 so as to form on top of each bar 3^a a pocket of longitudinal extent 95 coextensive with the bar that leads toward its air discharge slit. The constriction of the slit, due to the widening space below the angle α between the walls of the adjacent bars, lends the effect of a discharge nozzle to each slit, thereby concentrating the force of the air discharge through the slit and so facilitating and promoting the separation which the device is designed to effect. It also prevents the clogging of materials between the bars and produces a regular upward current of the air, preventing side currents, and the inclination of the upper surface of each bar forms with the front face 100 of the succeeding bar a pocket into which 110

the material will be retained temporarily while the values are permitted to gravitate therefrom.

In practice the box 8 is mounted in any usual or preferred manner upon mechanism adapted to agitate it or it may be manually agitated, and it is supplied upon the upper part of the floor with the raw material, such material being spread evenly over the floor 10 by the projections 2 passes in a thin sheet over the riffles. At each slit between the bars 3 of the riffles it meets an air blast supplied within the chamber 20 from the pipe 17. The force of the air discharge from 15 each slit, being as previously specified, augmented by the constriction of the slit, serves to drive out the lighter particles of the pulverulent mass of material while the heavier particles, or in other words the ore, drop by 20 gravity into a drawer 7 underneath, whence it may be taken upon opening of the drawer.

By aid of the wing screws 16 the supply of air to each drawer compartment may be regulated to any required extent.

25 Different sizes of bars 3 may be used with the effect of enlarging or diminishing the gage of the slits as desired, the bars being

made readily removable and interchangeable at will.

What I claim is—

1. In a concentrator, a casing, riffles comprising a series of bars disposed in spaced relation in a common plane therein, each bar having a substantially vertical front face, a rearwardly inclined upper face and a rear face inclining forwardly from said upper face, and means for delivering air currents upwardly between the bars. 35

2. In a concentrator, a casing, riffles comprising a series of bars disposed in spaced relation in a common plane therein, each bar having a substantially vertical front face, a rearwardly inclined upper face and a rear face inclining forwardly from said upper face, means for delivering air currents 40 upwardly between the bars, and means for feeding material in distributed form to said bars. 45

In testimony whereof I affix my signature in presence of two witnesses.

LOUIS BOWERMAN.

Witnesses:

EDWIN E. HECKBERT,
A. J. MATTER.
